UNITED STATES PATENT OFFICE

2,331,445

FULL OPENING LIGHTER

Alexander Sydney Weston, New York, N. Y.

Application April 3, 1942, Serial No. 437,536

1 Claim. (Cl. 67—7.1)

This invention relates to lighters for cigars, cigarettes, and pipes, and has for its main object to provide a device of this type which normally will be closed and the flame thereof extinguished, as usual, but which may open to permit the production of a flame thereon, and the flame extinguishing member thereof being adapted to be opened more conveniently than with lighters used hereinbefore to such an extent, that the flame produced may be more conveniently applied to a cigar, or cigarette, and particularly to a pipe.

Another object of this invention is to provide a device as characterized hereinbefore, which will be convenient and efficient to operate, to fully open, to light, or to close and extinguish the same with one hand, and which nevertheless will be quite inexpensive to manufacture, and easy and quick to assemble.

Still a further object of my invention is to provide a cigar, cigarette, and pipe lighter of the character indicated hereinbefore, the most important parts of which may be made by simple stamping, swaging, or cutting die operations eliminating the expensive screw machine or similar parts heretofore used in similar lighters.

Still further objects of this invention will be apparent as the specification of the same proceeds, and among others, I may mention to provide a device of the character described, which will be easy and quick to operate, or to put in an extinguished inoperative position, and which will have high-class wearing qualities and will be durable and reliable in use.

In the drawings forming a part of this specification and accompanying the same:

Fig. 1 is a front elevational view of my novel lighter;

Fig. 2 is a rear elevational view thereof;

Fig. 3 is a plan view of the same, all the mentioned three views showing my device as fully assembled and in a closed inoperative position, while

Fig. 4 is a sectional elevation thereof showing the same in an open operative position;

Fig. 5 shows a blank used to form the spark tube, and

Figs. 6, 6a, and 7 are longitudinal and transverse sectional views, respectively, of the assembled spark tube;

Figs. 8 and 9 are front and plan views of the arm stud used in my device, and

Figs. 10 and 11 are a plan view and a side elevational view, respectively, of the closing and opening arm for my device.

Referring now to the drawings more in detail, the numeral 20 indicates the main housing of my device, being preferably made of sheet metal and of the elongated flat oval shape shown in the drawings. An upper cap or cover 21 is secured at the one end of the housing 20, and a lower cap or bottom is secured at the other end by any appropriate means, as by having the respective flanges 21a and 22a, thereof, soldered on the housing 20.

As it is well known in this art, the housing 20 may be filled by a cotton or other absorbent material 23 which is charged with the flame producing fluid, like benzene, and a wick 24 is placed into said housing curling within the cotton, so as to conduct the liquid therein by capillary action upwardly to the flame producing end 24a of said wick which is protruding through a small tube 25 in the cover 21.

The bottom 22 may have an inwardly turned screw threaded tube portion 26, into which is screwed a closing plug 27, so that the device may be replenished or filled with the combustible fluid through said tube 26 when the plug 27 is removed.

A spark tube 28 is secured on the cover 21, said tube being formed of the sheet metal blank 29, shown in Fig. 5, the central portion 29a of said blank being formed into the tube proper 30 by bending the same in an appropriate manner, until the dotted lines 30a, 30a meet the two side extensions 31 and 32 of the blank being then brought into close over-lapping relation and being in such a position secured into the top or cover 21 of the device by any appropriate means, as by the teeth 31a and 32a passing through appropriate holes in the cover or top 21 and then being secure therein, or the whole lower end of the spark tube support being soldered into said cover or top.

Two appropriate extensions 31b and 32b are also provided on the blank 29 having apertured polygonal terminations 31c and 32c which form the bearings for the pin 33 of the spark producing wheel 34, as will be understood.

A flint or other spark producing material 35 is arranged in the tube 30 being pressed against the knurled spark wheel 34, as by the spring 36, the pressure of said spring being adjusted by the screw 31, as usual in such devices.

It will be understood that the spark is produced by rotating the knurled wheel 34 in such a direction that the spark produced by its friction on the flint 35 will be thrown against the flame producing end 24a of the wick 24, there-

by igniting the fumes of the combustible fluid, as is usual in such devices.

A protective and flame extinguishing cap 38 is also arranged in my device as is usual in such cases, its outer larger portion 39 closing both over the flame producing end 24a and over the wheel 34, having a cut-out portion 40 in its wall to fit over and avoid the spark tube 30, and having an inner tube 41 by which it will close on and extinguish the flame in the wick end 24a, as will be understood.

The protective and flame extinguishing cap 38 is secured at the end of a swinging arm 42 pivoted or rotatable on pin 43 secured across the top portion of the arm stud 44.

A curved flat arm locking spring 45 is secured by one of its ends 46 on the cover or top 21 adjacent to the wick tube 25, its other end 47 being raised above the cover or top 21 to a desired distance by the curve shown in said spring 45, and engaging the front 48 of a projection 49 at the pivoted end of the arm 42 when said arm is in a closed position, as indicated in Figs. 2 and 3, and in such a position, said spring by its pressure on the mentioned side of said projection will tend to keep the arm 42 in its closed downward position, indicated in said Figs. 2 and 3, and will have a tendency to counter-act the opening of said arm into the position shown in Fig. 4, since, until the front face 48 of said projection will leave the end 47 of spring 45, said spring will have a pressure thereon trying to close the arm 42 or to prevent its further opening and swinging in an upward and right hand direction, as indicated by the arrow 50 in Fig. 4. This tendency of said spring 45 will be operative until the arm 42 arrives into a substantially vertical position, its center line in said position being indicated in an imaginary manner by the dot and dash lines 42a, and upon a further turning of said arm in a right hand direction, it will further and fully open to a practically horizontal position, indicated with dot and dash line 42b in Fig. 4. In said position, the heel end 51 of the arm 42, that is, the portion of its end opposite to the projection 49, will engage the end 47 of the spring 45, and the pressure of said spring now will have a tendency to keep said arm 42 and the protective cap 38 in a fully opened horizontal position, indicated in Fig. 4.

The use and operation of my device will be obvious from the herein description, and it is very similar to those of many lighters now in use. The main differences between my lighter and other lighters of similar type at present in use, being the improvements in elements, construction and details, combinations and improved operation in my device over them.

When it is desired to use my device, the same may be operated with one hand and it will be grasped between the forefinger, middle fingers and the thumb of, let us suppose, the right hand of the user, the thumb resting for the time being against the right hand end 20a of the casing or housing 20, and the fore and middle fingers resting against the left end 30b of said housing, as will be understood. Thereupon the thumb will engage the lower end of the cap 38 and will swing the cap with its arm upwardly and rearwardly on the pivot or pin 43, as in-

dicated by the arrow 52, turning said cap and the arm 42 in the direction of arrow 50, until it will arrive to its fully open rearward horizontal position indicated in Fig. 4. In the last stage of such a movement, the housing 20 again may be caught by the thumb, and the arm moved to its fully open position by the aid of the forefinger.

The device being so open, the thumb may engage wheel 34, rotate it and produce the spark lighting the wick end 24a.

When it is desired to extinguish the flame and close the device, the forefinger will engage the rear of arm 42 and cap 38 and move it forwardly and downwardly in opposite direction to the one indicated by the arrows 50 and 52, until the cap will be entirely closed on the wheel 34 and tube 41 will close on the wick end 24a and extinguish the flame, as it will be understood.

I want to remark that the arm stud 44 is also made of special novel construction, being formed of a piece of sheet metal folded, forming a curved portion 44a in its blank having the two sides 44b ending in rounded upper portions 44c in which are the holes 44d for the pivot pin 43 of the arm 42. The sides 44b may also have downwardly projecting teeth 44e which will fit into appropriate openings provided in the top or cover 21 of my device and then the arm stud secured by riveting said projections or teeth 44e or by soldering, or by any other suitable methods.

The arm 42 also is of a novel improved construction, the same being made of one piece of material, preferably stamped out of sheet metal with the parts and contours shown in Figs. 10 and 11. At the one end thereof adjacent to the projection 49, it may be provided by an aperture or hole 53 for the pivot pin 43, and at the other end, it may have cross projections 54 and 55 to support and strengthen the adjacent side of the cap 38 and may have a transversely struck round flange portion 56 adjacent thereto with a hole 57 through which may pass a securing pin or rivet 41a for the cap 38 and the flame extinguishing tube 41, as also will be easily understood by those versed in this art. A vertical slot may be provided in the wall of the cap 38 to permit the neck 56a of round flange 56 to pass through said wall.

What I claim as new, is:—

In a lighter having a casing with a top of sheet material, a flint tube formed of a blank of sheet material, said blank having the usual rectangular center portion for the tube proper, supporting or leg portion on each of two opposite sides of said rectangle, the side edges of said leg portions being curved gradually narrowing to ends shorter than the respective sides of said rectangle, two extensions at a third side of said rectangle, each having a perforated head, so that upon an appropriate bending of the blank, said rectangle will be formed into a tube, said leg portions then being in registering relation, ears at the ends of said leg portions by which the same may be secured in holes in the top of the casing, and said perforated extensions being then adapted to receive the pin of a usual knurled flint disk.
